HYDRAULIC SYSTEM

Walter Ernst, Mount Gilead, Ohio, assignor to
The Hydraulic Development Corporation, Inc.,
Wilmington, Del., a corporation of Delaware

Application April 25, 1942, Serial No. 440,526

6 Claims. (Cl. 60—97)

This invention relates to hydraulic machinery and, in particular, to hydraulic systems including a plurality of fluid operable motors and a pressure fluid source of variable delivery, which is common to said motors, for supplying pressure fluid thereto, and has associated therewith a control device adapted, in response to a predetermined pressure acting on said control device, to reduce the delivery of the fluid source.

Heretofore, when trying to operate two or more hydraulic motors in a hydraulic system of the above mentioned type, it was always necessary to set the control device for the maximum pressure required in any of the hydraulic motors. In other words, even when the fluid pressure source, for instance, a variable delivery pump, was idling, it continuously had to maintain the highest pressure required in the hydraulic system, which caused rapid wear of the pump.

Accordingly, it is an object of this invention to provide a hydraulic system with a plurality of hydraulic motors and a pressure fluid source common thereto, which will overcome the drawback outlined above.

It is another object of the invention to provide a hydraulic system including a plurality of hydraulic motors and a pressure fluid source of variable delivery with a control device for varying the delivery, in which the control device may be set so that the pressure fluid source, when idling, operates only at the lower rather than the higher pressure required in the hydraulic system.

Still another object of the invention consists in the provision of a hydraulic system including a plurality of hydraulic motors and a variable delivery pump with servomotor means, in which the servomotor means may be set so that the pump may selectively be shifted to and held in substantially neutral or no delivery position in response to the lowest pressure required in the system.

It is a still further object of the invention to provide a hydraulic system with at least three hydraulic motors adapted respectively to be operated at different pressures by a common variable delivery pump with servomotor means, in which the pump may be held in idling position at the lowest pressure required in the hydraulic system.

These and other objects and advantages of the invention will appear more clearly in connection with the accompanying drawings, in which:

Figure 1 diagrammatically illustrates a first embodiment of the invention.

Figures 2, 3 and 4 show various positions of a

valve used in connection with the hydraulic system of Figure 1.

Figure 5 is a further embodiment of the invention.

General arrangement

According to the present invention, the variable delivery pump, adapted to supply pressure fluid to a plurality of hydraulic motors at different pressures, is provided with differential control plunger means, the largest area of which is continuously connected with the pressure side of the pump, while a smaller opposing area may selectively be connected with the pressure side of the pump when the latter supplies pressure fluid to a motor in the system which requires the maximum pressure obtainable in the hydraulic system.

Structural arrangement

Referring now to the drawings and Figure 1 thereof in particular, the hydraulic system shown therein comprises a high pressure motor, generally designated 1 and two low pressure motors, generally designated 2, 3. The motor 1 includes a cylinder 4 having reciprocably mounted therein a piston 5 with piston rod 6. The motors 1, 2 and 3 are adapted to be supplied with pressure fluid from a variable delivery pump 7, of any standard design, having a flow-control member 8, the position of which controls the delivery of the pump.

The pump 7 includes a casing 9 housing a spring 10, one end of which abuts a spring disc 11 adjustable by means of an adjusting screw 12. The other end of the spring 10 engages a head 13 of a control rod 14 which, in its turn, engages the flow-control member 8. The spring 10 continuously urges the flow-control member 8 into position for placing the pump 7 on full delivery stroke. The pump 7 has associated therewith a control mechanism, generally designated 15, which includes a casing 16 connected to the pump casing in any convenient manner. The casing 16 comprises a cylinder bore 17 and a chamber 18.

The cylinder bore 17 has reciprocably mounted therein a differential piston 19 with an extension 20 adapted to engage the flow-control member 8 and, in response to a predetermined pressure in the bore 17, to shift the flow-control member 8 against the thrust of the spring 10 toward the left, thereby shifting the pump 7 into substantially neutral or no delivery position. The outer end of the cylinder bore 17 is closed by a closure 21 connected to the casing 16 in any convenient manner, and provided with a bore 22 which, in

its turn, communicates with a conduit 23. The conduit 23 leads to a conduit 24 which communicates with the pressure side of the pump 7, while the suction side of the pump 7 is connected through a conduit 25 with a fluid reservoir or tank 26. The conduit 24 also communicates with a four-way valve 27, which comprises a valve casing 28 and a valve member 29 reciprocable in the casing 28.

The valve member 29 has two spaced pistons 30 and 31, of which the piston 30 is provided with radial slots 32, which are adapted, when the valve member 29 is in its intermediate position, to allow fluid communication between the upper portion of the valve casing 28 with the conduit 33. The valve member 29 also has a longitudinal bore 34 therethrough and is provided with an actuating shaft or handle 35, having a transverse bore 36 therethrough.

The conduit 33 communicates with a conduit 37 leading to the upper portion of the cylinder 4 pertaining to the motor 1, while the lower portion of the cylinder 4 communicates with a conduit 38 leading to the lower portion of the four-way valve 27. The lowermost end of the four-way valve 27 furthermore communicates with a conduit 39 leading to the conduit 25. Communicating with the conduit 37 is a pilot line 40 which leads to the chamber 18 of the control mechanism 15.

Communicating with the pressure line 24 is a conduit 41 leading to a conduit 42, which communicates with the four-way valves 43 and 44. These valves, in their turn, control the supply of pressure fluid to the motors 2 and 3 respectively. The valves 43 and 44 are four-way valves of any standard design with a neutral or intermediate position, in which no fluid is admitted to nor exhausted from the motors 2 and 3. If desired, the four-way valves 43 and 44 may be of the same construction as the four-way valve 27.

Connected to the four-way valve 43 are two conduits 45 and 46 respectively leading to the upper and lower portion of the cylinder 47 pertaining to the motor 2 which, in its fundamental structure, may be similar to the motor 1. Similarly, two conduits 48 and 49 connected to the four-way valve 44 lead to the cylinder 50 pertaining to the motor 3, which corresponds to the motor 2. A conduit 51, interconnecting the valves 43 and 44, constitutes an exhaust line and leads to the tank 26.

The various positions of the valve 27 are shown in Figures 2, 3 and 4, and will be discussed in connection with the operation of the device.

It may be assumed that it is now desired to operate the high pressure motor 1 without operating the motors 2 and 3, which are cut off from the conduit 41 by placing the valves 43 and 44 in neutral position.

It may further be assumed that the pump 7 is idling. To effect operation of the motor 1, the operator shifts the actuating shaft or handle 35 upwardly into the position of Figure 3, thereby causing a pressure drop in the pilot line 23 so that the spring 10 moves the pump 7 on full delivery stroke. The fluid expelled from the upper portion of the valve casing 28, during the upward shifting movement of the handle 35, passes through bores 36 and 34 into the exhaust line 39. When the valve member 29 has thus been shifted, it will be clear that pressure fluid from the pump 7 passes through conduit 24 into the conduit 33, and from there through conduit 37 into the upper portion of the cylinder 4, while the lower portion

of the cylinder 4 communicates through conduits 38 and 39 with the suction line 25. Fluid pressure prevailing in the conduit 37 is also conveyed through the pilot line 40 to the chamber 18 of the control mechanism 15. The piston 5 now performs its working stroke.

When, at the end or during any point of this working stroke, a predetermined maximum pressure has been built up in the upper portion of the press cylinder 4, this pressure acts through the pilot line 40 on the annular area 52 of the differential piston 19, while the same pressure acts through pilot line 23 on the larger differential area 53 of the piston 19. This differential pressure then causes the piston 19 to move into the position shown in Figure 1, thereby shifting the pump to substantially neutral or no delivery position. In other words, the pump 7 is now idling at the maximum pressure required in the hydraulic system.

If, at this time, it is not required to hold the piston 5 under its maximum pressure, the valve member 29 may be moved into intermediate or neutral position, in which instance the chamber 18 will be connected to the exhaust line 25 through the pilot line 40, conduit 33, slots 32, bores 36 and 34 and the conduit 39. Consequently, the pressure acting in the bore 17 of the control device 15 will not be opposed by pressure in the chamber 18 so that the pump 7 will be held in its idling position at a low pressure.

If it is desired to retract the piston 5, the operator shifts the shaft or handle 35 into the position of Figure 4, thereby again creating a pressure drop in the pilot line 23 so that the pump 7 is again moved into full delivery position by the spring 10. Pressure fluid from the pump 7 then passes through the conduits 24 and 38 into the lower portion of the cylinder 4, while the upper portion of the cylinder 4 is connected through the conduits 37 and 33, the bores 36 and 34 and the conduit 39 with the suction line 25. Consequently, the piston 5 moves upwardly.

When the piston 5 has reached the end of its retraction stroke, namely, the position shown in Figure 1, and is halted, the pressure in conduits 38 and 24 acts through pilot line 23 on the differential area 53 of the piston 19 so as to shift the pump 7 to neutral or no delivery position against the thrust of the spring 10. The operator may then shift the valve member 29 back into its neutral position, as shown in Figure 1. The hydraulic system is then again in its initial or idling position, shown in Figure 1. It will be noted that, in this position, pressure acts on the larger differential area 53 only and not on the smaller differential area 52, so that the pump 7 is held in its idling position at the lowest pressure required in the system.

If it is now desired to operate the low pressure motors 2 and 3, the operator shifts the valves 43 and 44 so as to establish fluid connection between the conduits 45 and 48 with the conduit 41, while simultaneously connecting the conduits 46 and 49 with the exhaust line 51. This causes a pressure drop in the pilot line 23 so that the spring 10 again shifts the pump 7 into full delivery position. Fluid pressure, therefore, passes through conduits 24 and 41 and the conduits 45 and 48 to the motors 2 and 3 respectively, while fluid expelled therefrom is exhausted through conduits 46 and 49 to the tank 26.

The fluid pressure prevailing in conduit 41 is conveyed through the pilot line 23 to the larger differential area 53 of the differential piston 19,

while the conduit 40 communicates through the conduit 33, slots 32, bores 36 and 34 and conduit 39 with the suction line 25. When a predetermined maximum pressure has been established in the conduits 45 and 48, which maximum pressure is lower than the required maximum pressure in the motor 1, the pressure in conduits 45 and 48 acts through pilot line 23 upon the larger area 53 of the differential piston 19 so as to cause movement of the pump 7 into substantially neutral or no delivery position.

To return the motors 2 and 3 to their initial position, the operator reverses the position of the valves 43 and 44, thereby again causing a pressure drop in the pilot line 23 so that the spring 10 again moves the pump 7 into full delivery position. Fluid pressure from the pump 7 then passes through conduits 41, 46 and 49 into the lower portion of the cylinders 47 and 50 respectively, thereby bringing about a retraction stroke of the motors 2 and 3.

When, at the close of this retraction stroke, a predetermined pressure has built up in the conduit 41, this pressure acts through the pilot line 23 on the larger differential area 53 of the differential piston 19 again, and returns the pump 7 to its neutral or no delivery position in the manner previously described. The valves 43 and 44 may now be shifted into neutral position so that the hydraulic system is again in its initial position. It will be noted that, in this position, the pump 7 again idles at the lowest required pressure in the system rather than at the maximum required pressure.

If it is desired to operate only one of the motors 2, 3, it is obvious that only the four-way valve pertaining to the motor to be operated is actuated, while the four-way valve pertaining to the other motor remains in its neutral position. It will furthermore be clear that, if desired, all the motors 1, 2 and 3 could be operated at the maximum pressure required in the system by shifting the three four-way valves 27, 43 and 44.

Referring now to the embodiment of Figure 5, the system shown therein is similar to that shown in Figure 1, and similar parts are, therefore, designated with the same reference numerals as in the system of Figure 1, however, with the additional letter *a*.

The system of Figure 5 differs from that of Figure 1 primarily in that the motors 1a, 2a and 3a are respectively operable at three different pressures. More specifically, the motor 1a is a high pressure motor, the motor 2a is a medium pressure motor, and the motor 3a is a low pressure motor. Furthermore, the control mechanism 15 of Figure 1 is replaced by a control mechanism 54, which comprises a casing 55 with three chambers 56, 57 and 58. Reciprocably mounted in the chamber 55 is a differential piston 59 having a larger differential area 60 and a smaller differential area 61. The piston 59 is furthermore connected with a control rod 62 for shifting the flow-control member 8a of the pump 7a. A sleeve-like floating plunger 63 is adapted to be acted upon by pressure fluid in the chamber 58, and to slide on the rod 62 so as to engage the piston 59.

The conduit system connecting the pump 7a with the high pressure motor 1a and low pressure motor 3a corresponds to that of Figure 1. The conduit system pertaining to the medium pressure motor 2a comprises a conduit 64 leading from the chamber 58 in the control mechanism 54 to the four-way valve 43a and is connected

by a branch line 65 with the upper portion of the cylinder 47a. The rest of the conduit system pertaining to the medium pressure motor 2a corresponds to the low pressure motor 2 of Figure 1.

The operation of the maximum pressure motor 1a in Figure 5 corresponds to that of the maximum pressure motor 1 of Figure 1. To effect a downward stroke of the piston 59, the operator shifts the valve handle 35a upwardly, thereby causing a pressure drop in the pilot line 23a so that the pump 7a moves on full delivery stroke and delivers pressure fluid into the upper portion of the cylinder 47a, while fluid expelled from the lower portion of the cylinder 47a is exhausted into the tank 26a. When a predetermined maximum pressure has been established in the upper portion of the cylinder 47a, this pressure, which is conveyed through the pilot line 40a into the chamber 57 to act on the smaller differential area 61 and is also conveyed through the pilot line 23a to the chamber 56 to act on the larger differential area 60, causes the differential piston 59 to move the pump 7a into substantially neutral or no delivery position, as shown in Figure 5.

To reverse the movement of the piston 59, the operator reverses the position of the valve handle 35a, thereby again bringing about a pressure drop in the pilot line 23a and causing the pump 7a to return to its full delivery stroke position. Pressure fluid from the pump 7a is then conveyed into the lower portion of the cylinder 47a, while fluid from the upper portion of the cylinder 47a is exhausted into the tank 26a. When a predetermined pressure, lower than the maximum pressure obtained during the downward stroke of the motor 1a, has been established, this pressure acts through pilot line 23a on the piston 59, so as to move the pump 7a to substantially neutral or no delivery position. It will be noted that the pilot line 40a is now connected to an exhaust or the tank 26a. The pump 7a, therefore, now idles at the lowest pressure required in the hydraulic system. The operator may now return the valve member 29a to its neutral position, as shown in Figure 5.

To operate the medium pressure motor 2a, the operator shifts the valve member pertaining to the valve 43a into its uppermost position so that a pressure drop occurs in the pilot line 23a, and the spring 10a returns the pump 7a to full delivery position. Pressure fluid then flows through the conduit 24a and the conduit 65 into the upper portion of the cylinder 47a, while fluid expelled from the lower portion of the cylinder 47a is exhausted through conduits 51a and 39a into the tank 26a. It will be clear from the drawings that the pressure prevailing in the conduits 24a and 65 is conveyed through the pilot line 64 into the chamber 58 and through pilot line 23a into the chamber 56. Consequently, the pressure prevailing in the chamber 58 brings the plunger 63 into engagement with the piston 59 so that the pressure acting on the area 60 has to overcome the pressure acting on the annular area 66 for moving the pump 7a toward neutral or no delivery position.

When a predetermined medium pressure has been established in the upper portion of the cylinder 47a, this pressure will move the piston 59 toward the left, thereby shifting the pump 7a into substantially neutral or no delivery position. The pump is now idling at a medium pressure. If the motor 2a is not to be held under pressure,

the valve 43a may be shifted into its neutral position so that the chamber 58 will be connected through conduit 64 and the slots 32a, the bores 36a and 34a and the conduit 51a with the tank 26a so that the pressure acting in the chamber 58 is not opposed by pressure in the chamber 58, with the result that the pump 1a will idle at the lowest pressure required in the hydraulic system.

To reverse the medium motor 2a, the operator shifts the valve 43a into its lowermost position, thereby again creating a pressure drop in the pilot line 23a so that the spring 10a returns the pump 1a to full delivery position. The conduits 64 and 65 are then connected to the tank 26a, while pressure fluid flows to the lower portion of the cylinder 41a through the conduit 46a. The motor 2a then returns to its upper position. When, at the end of this return stroke, a predetermined low pressure has been established, this pressure acts through the pilot line 23a on the piston 59 and moves the pump 1a to substantially neutral or no delivery position. The pump then idles at low pressure. The valve 43a may then be returned to its neutral position.

The operation of the motor 3a fully corresponds to the operation of the motor 3, so that no further description is required. When the predetermined maximum pressure required for the motor 3a has been established therein, which maximum pressure is lower than the required maximum pressure of the motor 1a and the motor 2a, the pump 1a is shifted to substantially neutral or no delivery position and then idles at low pressure.

From the above, it will be clear that the hydraulic system according to the present invention enables the operation of a plurality of motors at different maximum pressures respectively required for these motors without having to idle the pump at the highest required maximum pressure. On the contrary, the pump may idle at the lowest maximum pressure required, thereby saving considerably in power and materially increasing the life of the pump.

It will be understood that I desire to comprehend within my invention such modifications as come within the scope of the claims.

Having thus fully described my invention, what I claim as new and desire to secure by Letters Patent, is:

1. In a hydraulic system, a high pressure motor, a low pressure motor, each of said motors including a reciprocable plunger and fluid operable advancing and retracting means for actuating said plunger, a variable delivery pump for supplying pressure fluid selectively to said advancing or retracting means, means for continuously urging said pump into full delivery stroke position, pump control means for opposing the action of said urging means and including a differential piston with a larger area and a smaller opposed area, first conduit means continuously establishing fluid connection between the pressure side of said pump and said larger area, second conduit means continuously establishing fluid connection between said smaller differential area and the advancing means pertaining to said high pressure motor, and separate valve means for controlling the supply of fluid from said pump to each of said motors.

2. In a hydraulic system, a high pressure motor, a low pressure motor, each of said motors having associated therewith fluid operable advancing and retracting means for causing said motor to effect an advancing and a retracting

stroke, a pressure fluid source of variable delivery for selectively supplying pressure fluid to said advancing or retracting means of either of said motors, spring means for urging the fluid source

5 to full delivery position, pressure responsive control means for reducing the delivery of said fluid source, said control means comprising a differential plunger having a larger area continuously connected with a pressure line connected to said fluid source and having an opposed smaller differential area continuously connected with the advancing means of said high pressure motor, and separate valve means respectively associated with said high pressure and said low pressure motors for controlling the supply of fluid between said source and each of said motors.

3. In a hydraulic system, a high pressure motor, a low pressure motor, each of said motors having associated therewith fluid operable advancing and

20 retracting means for actuating said motors, a pressure fluid source for selectively supplying pressure fluid to said advancing or retracting means of either of said motors, control means associated with said fluid source for varying the

25 delivery thereof, means for continuously urging said control means into position to bring about maximum delivery of said fluid source, fluid pressure responsive mechanism operable to counteract said control means for reducing the delivery of said fluid source, said mechanism comprising a differential plunger with a larger area continuously connected to said fluid pressure source, and also comprising a smaller area opposed to the larger area and continuously connected with the

30 advancing means pertaining to said high pressure motor, and separate valve means respectively associated with said high pressure motor and said low pressure motor for controlling the supply of fluid from said fluid source to said motors and from said motors to an exhaust.

4. In a hydraulic system, a plurality of hydraulic motors, each requiring a different maximum operating pressure, each of said motors having associated therewith fluid operable advancing

45 and retracting means for actuating the respective motor, a fluid source common to said motors for supplying pressure fluid thereto, control means associated with said fluid source for varying the delivery thereof, means for continuously urging

50 said control means to bring about maximum delivery of said fluid source, pressure responsive mechanism for actuating said control means to reduce the delivery of said fluid source, said mechanism including a differential plunger having its largest effective area continuously connected to said pressure fluid source, and having a smaller effective area opposed to the largest area and communicating with the advancing means of one of said motors, and separate valve means for each motor controlling the flow of fluid between said source and each of said motors.

5. In a hydraulic system, a plurality of hydraulic motors, each requiring a different maximum operating pressure, each of said motors having

65 associated therewith fluid operable advancing and retracting means for actuating the respective motor, a fluid source common to said motors for supplying pressure fluid thereto, control means associated with said fluid source for varying the delivery thereof, pressure responsive means for

70 actuating said control means to reduce the delivery of said fluid source, said pressure responsive means including a differential plunger having its largest effective area continuously connected to a pressure line communicating with said pressure

fluid source, and having a smaller effective area opposed to the larger area communicating with the advancing means of one of said motors, means for continuously urging said control means to bring about maximum delivery of said fluid source, and a plurality of control valves respectively associated with said motors for controlling the flow of fluid to and from said motors, each of said control valves comprising a balanced valve member with a longitudinal bore therethrough hydraulically connected at one end with passage-ways on said valve member and connected at the other end with an exhaust.

6. In a hydraulic system, three motors respectively requiring three different maximum operating pressures, each of said motors including fluid operable advancing and retracting means for actuating said motors, a variable delivery pump common to said motors for selectively supplying pressure fluid to said advancing or retracting means,

means for continuously urging said pump into full delivery position, pressure-responsive means associated with said pump and including differential plunger means with three different effective areas, first conduit means continuously connecting the largest of said areas with the pressure side of said pump, second conduit means continuously connecting the second largest of said areas with the advancing means pertaining to the motor requiring the highest operating pressure, third conduit means continuously connecting the smallest of said effective areas with the advancing means pertaining to the motor requiring the second highest maximum pressure, said second and third areas being opposed to said first area and separate valve means for controlling the supply of fluid to the advancing or retracting means of each of said motors.

WALTER ERNST.
